CENTRIFUGAL CASTING MACHINE

Rodney E. Christian, Royal Oak, and Alfred W. Widerstedt, Detroit, Mich., assignors to Kerr Manufacturing Company, a corporation of Michigan

Application September 17, 1945, Serial No. 616,850

8 Claims. (Cl. 22—65)

1

The invention relates to centrifugal casting machines and has among its objects, first, the obtaining of a construction in which the work including the mold and the crucible for the molten metal can be quickly inserted within and removed from the centrifugal holder; second, to provide for accurately determining the pressure on the molten metal within the mold which is centrifugally developed; and, third, to provide adjustable means for counterbalancing exchangeable molds and crucibles. With these and other objects in view the invention consists in the construction as hereinafter described.

In the drawings:

Fig. 1 is a side elevation of the machine;

Fig. 2 is a plan view thereof;

Fig. 3 is an end elevation;

Fig. 4 is a cross section on line 4—4, Fig. 1, showing the centrifugal holder in position for loading with the mold and crucible;

Fig. 5 is a cross section on the line 5—5, Fig. 4;

Fig. 6 is a cross section on the line 6—6, Fig. 4; and

Fig. 7 is a section through the clutch.

As illustrated in Figs. 1 to 3, A is a frame including a base portion A' and spaced standards A². B is a cylindrical casing centrally provided with diametrically oppositely extending trunnions C and C' which are respectively mounted in bearings D in the standards A². E is a motor mounted on the base and F is a variable speed transmission between said motor and the trunnion C by which the latter and the casing B may be revolved at a predetermined speed.

The casing B has at one end a fixed head or closure G and at its opposite end a quickly removable and replaceable closure H. The latter is preferably formed by a cap having a flange H' overlapping the end of the casing and a series of spaced lugs H² thereon. H³ are pins extending radially inward from the flange H' which are adapted to pass through the spaces between the lugs H² and to interlock with the latter by a rotation of the cap. This forms in effect a bayonet joint by which the cap may be quickly locked to the casing after the loading of the latter with the work. The molds I are preferably of the type formed of investment compound retained within a cylindrical metal casing I'. At one end is a hopper-like recess I² for receiving the molten metal and which is connected by a sprue I³ to the mold cavity (not shown). J is a crucible in which the metal to be cast is melted in a suitable external furnace. This crucible is engageable with an annular seat member K preferably formed

2

of a metallic outer ring K' internally fitting and slideable within the cylindrical casing B and a refractory lining K² for directly engaging the crucible. The member K is yieldably supported by a coil spring member L, which also is within the casing B and has an abutment in the opposite end portion thereof. Thus, in loading the machine the crucible J containing the molten metal is removed from the furnace and inserted through the open end of the casing B into engagement with the seat member K. The mold I is then placed within the casing with its recessed end adjacent to the upper end of the crucible and bearing thereagainst, after which the cap H is engaged with and locked to the casing. This cap is provided with an adapter H⁴ for fitting the outer end of the mold I and holding it in registration with the crucible. During engagement of the cap the mold I is pressed inward which is permitted by the yielding of the spring L and the seat member K, the resilient pressure of said spring holding the crucible in sealing contact with the mold.

As the apparatus is designed for use with different molds requiring different quantities of molten metal for filling the same, it is essential to provide means for balancing the structure. For this purpose, exchangeable counterweights M are placed in the end of the casing adjacent to the head G. These are preferably annular in form constituting an abutment for the end of the spring L and the particular counterweight used is selected with respect to the weight of the mold and crucible together with its molten metal content. However, to obtain a more accurate balancing, provision is made for adjusting the counterweight M towards or from the axis of the trunnions C and C'. This, as shown, comprises a disc or head N engaging the outer end of the counterweight and centrally provided with a threaded bearing N' for engaging a threaded shank N² passing therethrough. The shank N² has a smooth portion N³ passing outward through a central aperture in the head G and provided at its outer end with a knob or handle N⁴ by which it may be rotated. A thrust bearing N⁵ engages the inner face of the head G and one or more guide rods N⁶ extending inward from the head G and passing through corresponding apertures in the disc N hold the latter against rotation. These guide rods also support an inner bearing N⁷ for the shank N². Thus, by rotating the knob N⁴, the counterweight N may be adjusted towards or from the axis of the trunnions into a position which accurately counterbalances the parts on the opposite side of said axis.

During the balancing operation the casing and its trunnions must be free to turn in their supporting bearings. This necessitates detachment therefrom of the driving mechanism and for this purpose a clutch O is arranged between the trunnion C and the variable speed transmission F. The purpose of the variable speed transmission is to enable the operator to regulate the speed of rotation of the centrifugal holder in accordance with the requirements for particular metals used in forming the casting. Any suitable mechanism may be used for this purpose such, for instance, as the "Reeves Drive." The details of this construction are not shown and it will be sufficient to state that by adjusting the motor E on the base A' towards or from the axis of the trunnions C and C', the speed of rotation of the driven member will be correspondingly reduced or increased.

The trunnions C and C' are attached to the casing B preferably through the medium of a ring Q, which latter engages an axially tapering seat Q' formed centrally on said casing. A clamping collar Q² having a screw-threaded engagement with the casing B holds the ring Q to its seat. The attachment between the ring and each of the trunnions is by a plurality of bolts Q³, the heads of which engage countersunk recesses in the inner face of the ring. The casing B is enclosed within an outer protecting casing R which, however, is cut away at the top for access to the upper end of the casing B during loading and unloading of the same. A speedometer mechanism S is connected to the outer end of the trunnion C and the indicator dial S' thereof is arranged at a convenient point on the casing R for observation by the operator.

Operation

In the operation of the machine, the operator first selects a counterweight M suitable for counterbalancing a particular mold and crucible and places this within the casing B adjacent to the disc N. The spring L is then placed within the casing to abut against the counterweight M and the seat member K is placed against the upper end of the spring in position to receive the crucible J. The mold I is then placed within the casing against the crucible J and is pressed inward and locked into position by the cap or closure H. The operator may then accurately balance the structure by shifting the counterweight M through the rotation of the screw-threaded shank N² by the knob or handle N⁴. When balance is attained, the mold and crucible are removed from the casing and the latter is placed within a furnace to melt the metal which is to be cast. When the molten metal is at the desired temperature, the crucible can be quickly transferred from the furnace to the open end of the casing B and engaged with the refractory seat K². The mold I is then placed against the crucible and the cap H is locked in position. Prior to the loading operation the casing B has been turned into upright position by means of the handwheel P. After loading is completed the clutch O is moved by its operating lever O' to couple the trunnion C with the transmission mechanism F. The motor is then energized to revolve the casing B and the speed of revolution of the latter is regulated to produce the desired pressure on the molten metal. Centrifugal force will throw the molten metal outward into the recess I² of the mold and through the sprue I³ into the mold cavity. The work is removed from the casing B by turning the casing into upright

position and removing the cap H. The mold and crucible may then be removed and the apparatus is in condition for repeating casting operation with another mold and crucible.

5 What we claim as our invention is:

1. In a centrifugal casting machine, a cylindrical casing mounted for revolution in a vertical plane about a central transverse axis, a heated crucible with molten content and a mold both insertable within said casing when in upright position through an open upper end thereof of the mold being inverted above and seated upon the top rim of said crucible, an annular member slidable within said casing and provided with a refractory lining forming a seat for said crucible, a helical spring coaxially arranged within said casing forming a resilient support for said annular member and holding the same on one side of the axis of rotation of said casing, and a closure for the open end of said casing adapted to press said mold into sealing contact with said crucible against the resilient pressure of said spring.

2. In a centrifugal casting machine, a cylindrical casing mounted for revolution in a vertical plane about a central transverse axis, a heated crucible with molten content and a mold both insertable within said casing when in upright position through an open upper end thereof of the mold being inverted above and seated upon the top rim of said crucible, an annular member slidable within said casing and provided with a refractory lining forming a seat for said crucible, a helical spring coaxially arranged within said casing forming a resilient support for said annular member and holding the same on one side of the axis of rotation of said casing, a closure for the open upper end of said casing adapted to press said mold into sealing contact with said crucible against the resilient pressure of said spring, and an annular exchangeable counterweight within said casing forming an abutment for said spring on the opposite side of said axis of rotation.

3. In a centrifugal casting machine, a cylindrical casing, a trunnion projecting laterally from the central portion of said casing, a bearing in which said trunnion is journaled, a detachable closure for one end of said casing, a heated crucible with molten content and a mold both insertable within said casing when in upright position with the closure removed the mold being inverted above and seated upon the top ring of said crucible, an annular seat for said crucible slidable within said casing, a helical spring coaxially arranged within said casing forming a resilient support for said seat whereby the engagement of said closure will press said mold into sealing contact with said crucible, a counterweight within said casing on the opposite side of the axis of said trunnion, means operable from without the casing for adjusting said counterweight towards or from said axis to balance the structure, means for rotating said trunnion and casing, and means for adjusting the speed of rotation of the latter.

4. In a centrifugal casting machine, a cylindrical casing, trunnions extending from diametrically opposite sides of the central portion of said casing, a frame in which said trunnions are journaled, a detachable closure for one end of said casing, a heated crucible with molten content and a mold both insertable within said casing when in upright position with the closure removed the mold being inverted above and seated upon the top ring of said crucible, an an-

5 nular seat slidable within said casing and provided with a refractory lining for engaging and supporting said heated crucible, a helical spring coaxially arranged within said said casing for resiliently supporting said seat, an annular counterweight in the casing on the opposite side of the axis of rotation of said trunnions and forming an abutment for said spring, a head adjacent to the outer end of said annular counterweight, a screw passing through and swiveled in the end of said casing adjacent to said head and threadedly engaging the latter whereby said counterweight may be adjusted by said screw towards or from the axis of said trunnion, rotating means for one of said trunnions, a clutch 15 between said rotating means and said trunnion, and manually operable rotating means on the other trunnion whereby said casing can be turned into upright position.

5. In a centrifugal casting machine, a cylindrical casing having an opening at one end thereof and mounted for revolution in a vertical plane about a central transverse axis, a resiliently yieldable seat within said casing movable lengthwise thereof, a closed bottom open top crucible engaging said seat with its open top facing toward the open end of said casing, a mold engaging said crucible and in communication with the open top thereof and a closure for the open end of said casing adapted to engage said mold and press the same into sealing contact with said crucible against the resilient pressure of said seat.

6. In a centrifugal casting machine, a cylindrical casing mounted for revolution in a vertical plane about a central horizontal axis and extending substantially equidistantly on opposite sides of said central axis, one end of said cylinder being open for substantially the full diameter thereof, a removable closure for the open end of said casing, a head at the opposite end of said casing, a spring sleeved within said cylindrical casing and extending from said head beyond said central axis toward said open end, an annular seat slidable within said casing and abutting said spring, a closed bottom open top crucible of a diameter to be inserted through the open end of said cylinder, a mold also insertable through the open end of said casing and adapted to engage the open top of said crucible, said spring being adapted to urge said mold and crucible toward said open end when said closure is removed and means for locking said closure to said casing against the resilient pressure of said spring.

7. In a centrifugal casting machine, a cylindrical casing having an opening at one end thereof and mounted for revolution in a vertical plane about a central transverse axis, a resiliently yieldable seat within said casing movable lengthwise thereof, a closed bottom open top crucible engaging said seat with its open top facing toward the open end of said casing, a mold engaging said crucible and in communication with the open top thereof, a closure for the open end of said casing adapted to engage said mold and press the same into sealing contact with said crucible against the resilient pressure of said seat, an exchangeable counterweight within said casing on the opposite side of said central axis from said closure, and means operable from outside said casing for adjusting said counterweight towards or from said central axis.

8. In a centrifugal casting machine, a cylindrical casing mounted for revolution in a vertical plane about a central transverse axis, said casing being adjustable to a position in which its longitudinal axis is vertical, one end of said cylindrical casing being open for substantially the full diameter thereof, a removable closure for the open end of said casing, a closed bottom open top crucible of a size to be inserted through said open end when said casing is in its vertical position with said open end upward, a refractory seat slidable within said casing for receiving said crucible, resilient yieldable supporting means for said seat, a mold insertable through the open end of said casing and adapted to rest on the open top of said crucible, said closure being engageable with the upper end of said mold to press the same and said crucible against said resilient supporting means, interlocking means between said closure and said casing, an exchangeable counterweight within said casing on the opposite side of said central axis from said mold, and means operable from outside said casing for adjusting said counterweight to counterbalance the load.
